UNITED STATES PATENT OFFICE.

CHARLES G. BIRDSALL, OF ELMHURST, NEW YORK, ASSIGNOR, BY MESNE ASSIGNMENTS, TO NATIONAL CARBON COMPANY, INC., OF NEW YORK, N. Y., A CORPORATION OF NEW YORK.

DRY CELL.

Application filed March 14, 1931. Serial No. 699,882.

This invention relates to improvements in dry cells and particularly to an improved form in which the depolarizing mixture of dry cells may be put up.

3 The present invention has for its object the provision of a new tablet compacted of depolarizing mixture and method of producing such tablet.

In a patent of Victor Yingye, No. 1,367,561, 10 patented Dec. 29, 1925, a dry cell mixture is described in which washers or tablets of depolarizing mixture are composed of separate, concentric rings of various grades of fineness, whereby the cell may be readily adapted to the particular type of service which it will have to render. The different layers or rings of such washers are separately molded or compacted and this makes the manufacture and assembly of the cells 15 relatively expensive.

In order to reduce the cost of manufacturing and assembling dry cells in which the depolarizing mix is divided into separate layers of different grades (as to carbon content, 20 bibulousness or other characteristics), in accordance with the present invention mixtures of all the required grades are simultaneously molded or compacted into a tablet. Preferably and in accordance with one of the features of the present invention, this is accomplished by feeding the various grades of mixture through concentric tubes into a die and then compacting the tablet that will thus be composed of concentric rings of depolarizing mixture varying in degree of fineness.

It will be obvious to those skilled in the art that tablets or depolarizing mixture in any other form may be thus compacted and 25 that the different layers may be arranged otherwise than in concentric rings.

In order more fully to explain the invention, a compacted tablet illustrated in Fig. 1 and a process of manufacturing it by 30 means illustrated in Fig. 2, will now be described.

As shown in Fig. 1, the compacted tablet has three concentric rings 1, 2 and 3 and it is perforated at the center 4. The hole 4 is 35 provided to permit the passage of a carbon electrode. The rings 1, 2 and 3 are of approximately the same thickness though, depending on the service required, this may be varied. Usually the ring 3 adjacent to the 40 carbon electrode will be of the finest mixture

and contains the highest percentage of carbonaceous material (e. g., graphite), and the outer ring 1 will be of the coarsest mix and may contain an inert absorbent material such as sawdust, shredded paper or the like. The 45 ring 2 should be of a mixture of intermediate fineness. The compositions of the mixtures will of course vary, depending on the particular requirements.

The tablet illustrated in Fig. 1 is preferably compacted in the manner illustrated in Fig. 2. The different grades of depolarizing material are placed in hoppers which communicate with a cylindrical chamber 4 and two annular chambers 5 and 6 surrounding it. The finest mixture will flow therefore through a pipe 7 into which it is distributed from the chamber 4. The mixture of medium fineness will flow through a pipe 8 surrounding pipe 7, and the coarsest mixture 50 will flow through a pipe 9 surrounding the former. Under the control of suitable mechanism well known in the art of tablet making, a predetermined quantity of each grade of mixture is deposited within a die 55 10. Then the lower part of the pipes 7, 8 and 9 are swung away from the die 10, the pipes being hinged at 11. Then the punches 12 and 13 are brought together at a pressure sufficient to compact the mixture into a tablet 60 of the desired strength. The punches 13 and 12 are provided with a core pin 14 and the corresponding aperture 15 to make a hole 16 through the center of a tablet of the necessary size to accommodate a carbon electrode. 65

What I claim is:

1. The process of preparing bodies of compacted depolarizing mixture for use in dry cells which consists in preparing a plurality of grades of mixture, forming them into layers, and simultaneously compacting said layers.

2. The process of preparing bodies of compacted depolarizing mixture for use in dry cells which consists in preparing a plurality of grades of mixture, forming them into concentric rings, and compacting the mixture.

3. The process of preparing bodies of compacted depolarizing mixture for use in dry cells which consists in preparing a plurality of grades of mixture differing from each other in carbonaceous content, simultaneously feeding the different grades into a die to form a plurality of layers therein, and finally compacting the layers.

4. The process of preparing bodies of compacted depolarizing mixture for use in dry cells which consists in preparing three grades of mixture differing from each other in carbonaceous content and bibulousness, simultaneously feeding said grades of mixtures into a die through three concentric tubes, compacting the mixture in the die, and removing the compacted tablet from the die. In testimony whereof, I have signed my name to this specification this 8th day of March, 1924.

CHARLES G. BIRDSALL.
